UNITED STATES PATENT OFFICE

94,684

DESIGN FOR A SHOE

Nicholas J. Grossman, Lynn, Mass.

Application January 2, 1935, Serial No. 54,667

Term of patent 3½ years

To all whom it may concern:

Be it known that I, Nicholas J. Grossman, a citizen of the United States, residing at Lynn, in the county of Essex and State of Massachusetts, have invented a new, original, and ornamental Design for a Shoe, of which the following is a specification, reference being had to the accompanying drawing, forming a part thereof, in which

The figure is a view in perspective of a shoe showing my design, the outline of the heel being conventional and shown in dot and dash lines.

Both sides of the shoe are substantially alike in appearance.

I claim:

The ornamental design for a shoe substantially as shown and described.

In testimony whereof, I have affixed my signature hereto.

NICHOLAS J. GROSSMAN.
